UNITED STATES PATENT OFFICE.

HENRY F. EBERT, OF BROOKLYN, NEW YORK.

BRUSH.

SPECIFICATION forming part of Letters Patent No. 716,690, dated December 23, 1902.

Application filed September 11, 1902. Serial No. 122,944. (No model.)

To all whom it may concern:

Be it known that I, HENRY F. EBERT, a citizen of the United States, and a resident of the city of New York, borough of Brooklyn, in the county of Kings and State of New York, have invented a new and Improved Brush, of which the following is a full, clear, and exact description.

The invention relates to brushes in which the bristles are bound in position by a cord or like flexible binder.

The object of the invention is to provide certain new and useful improvements in brushes, mainly in lather and paint brushes, whereby the bristles are securely fastened in position in the socket and are not liable to break when the brush is in use, and at the same time the cord or flexible binder is prevented from becoming loose or broken, thus insuring long life to the brush.

The invention consists of novel features and parts and combinations of the same, as will be more fully described hereinafter and then pointed out in the claims.

A practical embodiment of the invention is represented in the accompanying drawings, forming a part of this specification, in which similar characters of reference indicate corresponding parts in all the views.

Figure 1 is a perspective view of the improvement. Fig. 2 is a sectional side elevation of the same. Fig. 3 is an enlarged perspective view of the socket or ferrule. Fig. 4 is a side elevation of a sectional ferrule, the sections being shown spaced apart; and Fig. 5 is a sectional side elevation of the improvement provided with the sectional ferrule shown in Fig. 4.

The handle A of the brush is provided with a short shank A', on which is fastened the ring B' of a socket or ferrule B, preferably made of metal and projecting beyond the shank A' to receive the butt-ends of a bunch of bristles C, as plainly indicated in Fig. 2, the inner end of the socket abutting against a flange A², formed on the handle A at the beginning of the shank A'. The socket B (shown in Figs. 2 and 3) is provided with prongs B², extending integrally from the inner ring B', and sundry of the said prongs B² are fastened by solder or other means B³ to an outer ring B⁴, terminating at its outer edge

in an outwardly-turned flange B⁵, which forms an abutment for a cord or flexible binder D, wound around the socket between the flanges 55 A² and B⁵, so that the flexible binder cannot slip off the ferrule onto the bristles, and thus become loose.

The free ends of the prongs B² which are not fastened to the outer ring B⁴ terminate 60 close to the inner edge of the flange B⁵, and when the cord or flexible binder D is wound spirally around the socket it is evident that the said free ends of the prongs B² are bound firmly down upon the bristles within the 65 socket to securely hold the same in place.

The socket or ferrule B (shown in Figs. 4 and 5) is made in sections, of which one consists of an inner ring B⁶, having prongs B⁷, and the other section consists of an outer ring B⁸, 70 having a flange B⁹ and prongs B¹⁰ adapted to extend into the inner ring B⁶ to be fastened with the latter by nails or screws E' to the shank A' of the handle A, as plainly shown in Fig. 5. The free ends of the prongs B⁷ extend over the outer ring B⁸ close to the flange B⁹, and the flexible binder is wound around the ring B⁸ and its prongs B⁷ between the handle-flange A² and the ferrule-flange B⁹, the same as above described in reference to 75 80 Fig. 2.

Now when the brush is in use and is dipped into paint, water, or the like then the bristles in the socket or ferrule begin to swell and the flexible binder begins to contract to 85 a certain extent, so that the bristles are very firmly held in place in the socket or ferrule, especially as the bristles can readily swell into the space between adjacent prongs B², B⁷, or B¹⁰. Thus the bristles are held against 90 turning in a bunch in the socket or ferrule.

It is understood that the bristles C are provided at their ends with the usual cement to cause the bristles to adhere to each other and to securely fasten the bristles in place against 95 the face of the shank A' and the socket B. In manufacturing the brush the ring B' of the socket is secured by nails or other fastening means E to the shank A' of the handle and then the abutting end of the bunch 100 of bristles with the cement on the butt-end is placed in position in the socket and then the flexible binder D is wound around the prongs and the ring B' to fill the space between the

flanges A² and B⁵ completely, as plainly indicated in Figs. 1 and 2, the ends of the flexible binder being fastened in the usual manner.

Now by the arrangement described it will be seen that the outwardly-turned flange B⁵ or B⁹ of the socket permits free bending of the bristles at the outer end of the socket, and at the same time the said flange B⁵ or B⁹ forms an abutment for the flexible binder D to prevent the latter from coming in contact with the bristles or the lather and water or paint usually adhering to the bristles when in use, so that the flexible binder is not injured or broken, and consequently long life of the brush is insured.

Having thus described my invention, I claim as new and desire to secure by Letters Patent—

1. A brush comprising a handle, a socket for the reception of the butt-ends of the bristles secured at its inner end to said handle, a flange for the outer end of said socket, prongs extending from the inner end of said socket to the flange, and a binding for said prongs.

2. A brush comprising a handle, a socket for the reception of bristles secured to said handle, a flange for said socket, prongs extending from the inner end of the socket to the flange, and flexible binding means wrapped around said prongs between the inner end of the socket and the flange for retaining the bristles in position.

3. A brush comprising a handle having a shank, an annular flange at the beginning of the shank, a socket having an inner ring, prongs on the inner ring, an outer ring provided with an annular flange, the said inner ring of the socket being attached to the said shank and the socket being adapted to re-

ceive a bunch of bristles, and a flexible binder wound around the inner ring and the prongs, between the flange on the handle and the flange on the outer ring, as set forth.

4. A brush provided with a socket for the reception of bristles, and comprising an inner ring for attachment to the brush - handle, prongs extending from the inner ring, an outer ring onto which extend the terminals of the said prongs, and an outwardly-extending flange on the outer end of the said outer ring, as set forth.

5. A brush provided with a socket for the reception of bristles and comprising an inner ring for attachment to the brush - handle, prongs extending from the inner ring, an outer ring carried by sundry of the said prongs, the remaining prongs extending with their free ends on the outer face of the outer ring, and an outwardly-extending flange on the outer edge of the said outer ring, as set forth.

6. A brush comprising a handle, a socket for the reception of bristles and consisting of an inner ring secured to the handle, prongs extending from the inner ring, an outer ring carried by sundry of the prongs, an outwardly-extending flange on the said outer ring, and a flexible binder wound around the prongs and the inner ring and abutting against the said flange on the outer ring, as set forth.

In testimony whereof I have signed my name to this specification in the presence of two subscribing witnesses.

HENRY F. EBERT.
